[57]

ABSTRACT

This disclosure deals with a packing machine for packing or filling an empty case with a stack of articles such as cigarette cartons. The cartons are received from a cigarette tax stamping machine which opens the flaps on one side of each carton, affixes a tax stamp to each package, and applies glue to the opened flaps for resealing the cartons. The packing machine includes a case positioning tower which receives empty cases and successively positions the cases on a loading platform. A plurality of cartons are stacked in tiers in a magazine with the glued flaps extending upwardly, and are moved by a pusher assembly into an empty case on the loading platform, thus filling the case. The height and width dimensions of the magazine are adjustable in order to accommodate cartons of different lengths and thicknesses and the tower includes means for centering each case, regardless of width, on the platform. An ejector assembly is provided to move a case off the loading platform after it has been filled and position another empty case on the loading platform for filling. In addition, the apparatus includes means for turning a case end-for-end in order to place the glued flaps on the undersides of the respective cartons and thereby obtain an effective seal.

CASE PACKING MACHINE

Allan C. Davis U. S. Pat. No. 3,477,198 discloses a machine which automatically accumulates or stacks a number of cartons of cigarettes in tiers, each tier including a plurality of cartons, and packs the cartons into an empty case. The machine further includes structure for positioning a case in location for being packed with cartons. The machine disclosed in the above-mentioned patent is particularly advantageous in that it is able to accommodate cartons of cigarettes of different lengths, such as the regular, king-sized and imperial length cigarettes. The machine is not, however, capable of accomodating cigarettes of different thicknesses, such as standards and "thins." In addition, when using a machine of the character disclosed in the above-mentioned patent, each carton of cigarettes must be turned over before it is fed into the carton accumulating mechanism.

It is therefore an object of the present invention to provide an improved case packing machine which is capable of handling cartons of cigarettes of different lengths and thicknesses, and wherein it is not necessary first to turn the cartons over before they are fed into the case packing machine. A machine embodying the invention comprises an input conveyor for moving cartons onto an elevator of the case packing apparatus, the cartons moving in a direction which is transverse to their long dimension and having their glued flaps on the upper sides thereof, means for moving the elevator upwardly when it is filled with cartons, means for holding the cartons on the input conveyor stationary during movement of the elevator, a magazine located above the elevator and positioned to receive the cartons from the elevator when the elevator is moved upwardly, the width dimensions of both the magazine and the elevator being adjustable in order to accommodate cartons of different widths and the height dimension of the magazine being adjustable in order to accommodate cartons of different heights, a loading platform, a tower for positioning an empty case on the platform and centering the case relative to a stack of cartons, the centering means being able to accommodate cases of different widths, pusher means for moving a stack of cartons from the magazine into a case on the platform, the pusher means acting in response to the total height of a stack of cartons being equal to the height of the associated case in the tower, means for ejecting a filled case from the tower and means for turning the case end-for-end and thus placing the glued flaps for each carton on the underside thereof in order to apply pressure on the glued flaps to seal them.

The foregoing and other objects of the present invention will become apparent from the following detailed description taken in conjunction with the accompanying figures of the drawings, wherein:

FIG. 1 is a schematic plan view of a system for removing cartons of cigarettes from a case, opening each carton and applying transfers or stamps to the cigarette packages therein, closing each carton after applying glue, and repacking the cartons in empty cases;

FIG. 2 is a schematic elevational view taken on the line 2-2 of FIG. 1;

FIG. 3 is an enlarged view taken on the line 3-3 of FIG. 1;

FIG. 4 is a fragmentary elevational view taken on the line 4-4 of FIG. 3;

FIG. 5 is a fragmentary enlarged view taken on the line 5-5 of FIG. 4;

FIG. 6 is a sectional view taken on the line 6-6 of FIG. 3;

FIG. 7 is an enlarged sectional view taken on the line 7-7 of FIG. 6;

FIG. 8 is an enlarged sectional view taken on the line 8-8 of FIG. 6;

FIG. 9 is a fragmentary enlarged sectional view taken on the line 9-9 of FIG. 3;

FIG. 10 is a fragmentary sectional view taken on the line 10-10 of FIG. 9;

FIG. 11 is an enlarged fragmentary sectional view taken on the line 11-11 of FIG. 3;

FIG. 12 is a fragmentary sectional view taken on the line 12-12 of FIG. 11;

FIG. 13 is a fragmentary enlarged sectional view taken on the line 13-13 of FIG. 3;

FIG. 14 is a fragmentary enlarged sectional view taken on the line 14-14 of FIG. 4;

FIG. 15 is a view generally similar to FIG. 12 but showing another position of the parts;

FIG. 16 is an enlarged fragmentary sectional view taken on the line 16-16 of FIG. 3;

FIG. 17 is a view generally similar to FIG. 16 but showing another position of the parts;

FIG. 18 is an enlarged fragmentary elevational view taken on the line 18-18 of FIG. 1;

FIG. 19 is a plan view taken on the line 19-19 of FIG. 18;

FIG. 20 is a fragmentary sectional view taken on the line 20-20 of FIG. 18;

FIG. 21 is a fragmentary sectional view taken on the line 21-21 of FIG. 20;

FIG. 22 is an enlarged fragmentary view taken on the line 22-22 of FIG. 20; and

FIG. 23 is a schematic electrical diagram of a control circuit of the structure shown in FIGS. 18 through 22.

With reference to FIGS. 1 and 2, a cigarette processing system including a case packing machine embodying the present invention comprises a supply conveyor 26, which feeds filled cases to an unloading platform 27 where an operator stands. The cases are received at the unloading platform with one side wall cut away to expose the ends of the cigarette cartons in the case. The operator removes the cartons of cigarettes from the cases and places the cartons on a conveyor 28 which feeds the cartons to a stamping and gluing machine 29 wherein the flaps along a side of each carton are opened, a stamp or transfer is applied to an end of each cigarette package and glue is applied to an opened flap of each carton. Another conveyor 31 receives the cartons from the stamping and gluing machine 29, and feeds the cartons to a case packing machine 32 wherein the cartons are repacked in the case from which they were removed. The cartons moving on the conveyor 31 have their opened flaps extending upwardly and their long dimension is transverse to their direction of movement. An output conveyor 33 receives the refilled cases from the case packing machine 32, and an inverter 34 connected in the conveyor 33 turns each case end-for-end to place the opened flaps on the undersides of the cartons.

With reference to FIG. 2, the case packing machine 32 includes an inclined overhead belt conveyor 36 which slants from the unloading platform 27 upwardly to a tower of the case packing apparatus. After the op-

erator standing at the platform 27 removes the cigarette cartons from a case, he places the emptied case, such as the case indicated by the reference numeral 37 in FIG. 2, on the conveyor 36 with the open side of the case 37 facing downwardly. The conveyor 36 moves the empty case 37 upwardly and toward the right as seen in FIG. 2 to the top of the tower where it falls by gravity into the tower, as will be described hereinafter.

The stamping and gluing machine 29 may be generally of the character disclosed in applicant's U. S. Pat. No. 3,513,616 entitled "Transfer Applying Method and Apparatus." However, the system disclosed herein does not include a mechanism at the output of the machine 29 for turning the cartons over, as does the machine disclosed in the above-mentioned patent.

With particular reference to FIGS. 3 and 11, the input conveyor 31 comprises an endless belt 46 which is trained around a pair of rollers rotatably mounted at the opposite ends of the conveyor 31. One of the two rollers is shown in FIG. 11 and is indicated by the reference numeral 47, this roller 47 being driven in the clockwise direction as seen in this figure. A drive illustrated in FIG. 9 turns the roller 47 and the belt 46, this drive comprising an electric motor 48 which is connected by pulleys 50 through 55 and belts 58 through 60 to the pulley 56. The pulley 56 is secured to a shaft 57 which is rotatably mounted on the frame of the machine and supports the roller 47. The electric motor 48 is preferably continuously energized during operation of the machine and, consequently, the drive roller 47 and the belt 46 will be continuously turned in order to urge cartons of cigarettes toward the case packing machine.

As shown in FIGS. 1 and 11, and as mentioned previously, cartons of cigarettes, indicated generally by the reference numeral 66, are received from the stamping and gluing machine 29 and moved on the belt 46 with their long dimension extending transversely of the direction of movement of the belt 46. Also as previously mentioned, the stamping and gluing machine 29 opens the flaps, indicated by the numeral 66a, along one side of each carton 66 and, after a transfer or stamp has been placed on the cigarette packages therein, a bead of glue is applied to one of the opened flaps 66a of each carton. The two opened flaps 66a of each carton are not pressed together, however, until they are stacked in a magazine of the packing machine, as will be described hereinafter.

The case packing machine 32 comprises a frame 39 which supports the various parts of the machine, and a vertically movable elevator 40 (FIGS. 11 and 12) which is located at the forward end, considered in the direction of movement of the cigarette cartons, of the input conveyor 31. The elevator 40 receives cartons of cigarettes from the conveyor 31 and loads them into an accumulator or magazine 41 (FIGS. 3, 16 and 17) which receives successive tiers, each consisting of six cartons. A tower 42 located adjacent the magazine 41 receives empty cases from the conveyor 36 and positions the cases adjacent the magazine, and a pusher assembly 43 (FIGS. 6 to 8) pushes a stack of cartons from the magazine into an empty case in the tower 42. An ejector mechanism of the tower 42 then pushes the filled case from the tower 42 onto the output conveyor 33.

With particular reference to FIGS. 11 and 12, as mentioned above, the elevator 40 is located at the for-

ward end of the conveyor 31 and underneath the magazine 41. The elevator 40 includes a horizontal plate 67 and a generally vertically extending plate 68 which in the present instance is formed integrally with the plate 67 and extends downwardly therefrom closely adjacent the forward end of the conveyor 31. The purpose of the vertically extending plate 68 is to provide positive assurance that cartons will not be fed into the packing machine while the elevator 40 is in an upwardly displaced position. To support the elevator 40 and to move it upwardly and downwardly, a pneumatic cylinder 71 has its upper end fastened to the frame 39 of the machine by a bracket 70 below the horizontal plate 67, and the piston rod 72 of the cylinder 71 is connected 10 to a bracket 73 (FIG. 15) fastened to the underside of the plate 67. The vertical movement of the plate 67 is guided by a pair of guide rods 74 and 75 which are also fastened to the bracket 73 and extend generally parallel to the piston rod 72 (FIG. 15), the lower ends of the 15 two rods 74 and 75 being secured to a bracket 77. The cylinder 71 has a sliding fit in a center opening in the bracket 77 and consequently when air is admitted to the cylinder 71 below the piston, the rods 72, 74 and 75, the bracket 77, and the plate 67 are moved upwardly from the position shown in FIGS. 11 and 12 to the position shown in FIG. 15. To retract the elevator after it has reached the limit of its upward movement, an electrical limit switch 78 (FIGS. 12 and 15) is mounted on the frame of the machine adjacent the 20 guide rod 74, and a cam 79 secured to the guide rod 74 actuates the limit switch 78 when the elevator 40 reaches its upper limit.

The admission of air pressure to the upper and lower ends of the cylinder 71 in order to lower and raise the plate 67 is controlled by a solenoid actuated air valve 71a (FIG. 3). The switch 78 actuates the valve 71a to retract the rod 72 and the plate 67, and another limit switch 81 mounted at the forward side of the elevator actuates the valve 71a to extend the rod 72 and the plate 67. A right-angle shaped plate 82 (FIG. 11) including an upwardly extending section 83 is slidably fastened to the plate 67 of the elevator, and a slot 83b (FIG. 11) is formed in the section 83 in front of the switch 81. When the elevator is in its lowered position, shown in FIG. 11, the slot 83b extends from just above the switch 81 downwardly to the lower end of the section 83. A horizontal section 83a of the plate extends under the plate 67 and is slidably mounted between two guides 84 on the underside of the elevator plate 67.

During operation of the machine, cartons are pushed by the conveyor 31 on the plate 67 when it is in its lowest position (FIGS. 11 and 12), each carton on the plate 67 being pushed by the next succeeding carton. The cartons push the sliding plate 82 forwardly until the forwardmost carton on the plate 82 engages and actuates the switch 81 (FIG. 11) to move the elevator upwardly (FIG. 15), which in the present construction occurs when there are six cartons on the elevator. It will be noted that the sliding plate thus forms an adjustable extension of the plate 67 of the elevator.

The switch 81 therefore actuates the valve 71a to move the elevator 40 upwardly when there are six cartons on the plate 67, and the switch 78 actuates the valve 71a to retract the elevator as soon as the plate 67 has reached the uppermost limit of its movement. As will be explained hereinafter, another switch is actuated when tiers of cartons of a certain height are accu-

mulated in the magazine and this latter switch is connected in circuit with the valve 71a and the switch 78 to prevent retraction of the plate 67 while the cartons are being pushed into a case.

To hold the cartons 66 in the magazine 41 after the elevator 40 moves downwardly, a pair of movable hold or rest bars 86 and 87 (FIGS. 11, 12, 15 and 16) are provided at the bottom of the magazine 41. With reference to FIG. 16, the two rest bars 86 and 87 extend transversely of the cigarette cartons 66 in the elevator 40 and are supported by braces 85 adjacent the ends of the cartons 66. Two pneumatic cylinders 88 and 89 (FIG. 17) are connected between adjacent ends of the bars 86 and 87, and the cylinders 88 and 89 move the bars 86 and 87 between an inner "hold" position shown in full lines in FIG. 17 and an outer "release" position shown in dashed lines in FIG. 16. When the bars 86 and 87 are in their hold positions, they are sufficiently close together that they extend underneath the ends of any cartons 66 in the magazine and prevent the cartons from falling downwardly. However, when the bars 86 and 87 are moved apart by the pneumatic cylinders 88 and 89 to their withdrawn positions, they are sufficiently distant that the cartons 66 may move between them. As shown in FIG. 12, the width of the elevator plate 67 is less than the distance between the bars 86 and 87 when in their hold positions, so that the elevator can move downwardly between the bars 86 and 87 even though the bars are in their hold positions.

Thus, when the elevator 40 is moved upwardly with a tier of six cartons 66 thereon, the hold bars 86 and 87 are moved apart by the pneumatic cylinders 88 and 89 just prior to the time that the cartons 66 reach the bars 86 and 87. After the tier has been moved upwardly above the bars 86 and 87, the cylinders 88 and 89 are actuated to pull the bars 86 and 87 to their hold positions where they extend underneath the ends of the cartons, as shown in FIG. 16. The elevator 40 then moves downwardly between the bars 86 and 87, permitting the tier of cartons 66 to come to rest on the bars 86 and 87. In the event there are one or more tiers of cartons already in the magazine 41 when a tier of cartons is moved upwardly, the cartons on the elevator engage the undersides of the cartons already in the magazine and move them upwardly one tier level.

The cylinders 88 and 89 are actuated to move the rest bars 86 and 87 between their hold and release positions by a cam 91 (FIG. 11) fastened to the back of the vertically extending plate 68 of the elevator 40. The cam 91 is in a position to actuate an air valve 92 fastened to the frame of the machine when the elevator moves upwardly. The valve 92 includes a roller 93 rotatably fastened to the outer end of a link 94, the link 94 in turn being pivotally connected to an arm 96 (FIG. 11). When the arm 96 is pivoted in the clockwise direction as seen in FIG. 11 about its mounting pin 97, it actuates the valve 92. The link 94 is pivotally mounted on the arm 96 by another pin 98 such that the link 94 may pivot from the position shown in FIG. 11 in counterclockwise direction about the pin 98 to a position where it is folded against the arm 96. The link 94 is spring urged to the position shown in FIG. 11 where it is at substantially a right angle to the arm 96.

When the plates 67 and 68 of the elevator 40 are moved upwardly, the curved upper end 91a of the cam 91 engages the roller 93 and pushes it toward the right as seen in FIG. 11. Since the link 94 cannot pivot on the

pin 98 any farther than the position shown in FIG. 11, the arm 96 is pivoted in a clockwise direction about the pin 97 thus actuating the valve 92 to energize the two cylinders 88 and 89 and move the bars 86 and 87 to their withdrawn positions. The cam 91 is located to retract the bars 86 and 87 before the cartons on the plate 67 reach them. The roller 93 rides against a vertically extended surface 91b of the cam 91 as the elevator 40 continues its upward movement and then rolls off the lower end of the cam 91 after the cartons on the elevator are above the hold bars 86 and 87. Once the lower end of the cam 91 is above the roller 93 the valve 92 is no longer actuated and the pneumatic cylinders pull the hold bars 86 and 87 inwardly to their hold positions. When the elevator 40 subsequently moves downwardly, due to the actuation of the switch 78 as previously explained, the lower end of the cam 91 again engages the roller 93, but in this direction of movement of the cam the link 94 is able to pivot downwardly in the counterclockwise direction about the pin 98 and fold against the side of the arm 96, with the result that the valve 92 is not actuated during downward movement of the elevator 40.

To hold the cartons on the belt and to prevent tilting of the carton which is closest to the elevator 40 when the elevator 40 moves upwardly, a pressure bar 101 is provided (FIGS. 3, 11 and 12) above the forward end of the belt 46. The bar 101 extends transversely beyond the sides of the belt 46 and its ends are slidably connected to two guide rods 104 secured to the frame of the machine. The pressure bar 101 is movable between a lower pressure applying position, shown in FIG. 11, and an upward release position by a pneumatic cylinder 102 (FIGS. 3, 11 and 12). The cylinder 102 is secured to the frame of the machine by a bracket 103 located above the plate 101, and the piston rod 102a of the cylinder 102 extends downwardly from the cylinder and is connected to the bar 101. When cartons 66 of cigarettes are being fed onto the horizontal plate 67 of the elevator 40, actuation of the switch 81 when the elevator is filled with six cartons both causes the elevator 40 to start moving upwardly and also actuates the cylinder 102 to force the pressure bar 101 downwardly and clamp the forwardmost cigarette carton on the belt 46. This carton is therefore held firmly as the belt 46 slides under it. This carton is thus prevented from tipping or cocking when the elevator is moving upwardly, and a vertically upwardly extending plate portion 159 of the pressure bar 101 prevents the cartons on the elevator from catching on the lower edge of the rearward wall of the magazine when the elevator moves up. When the elevator has reached its upper position, the pressure bar 101 is withdrawn upwardly by the cylinder 102 in response to actuation of the switch 78 but the vertical plate 68 prevents forward movement of the cartons by the belt 46 until the plate 67 is again in its lower position.

The magazine 41 into which the elevator 40 moves the tiers of cartons comprises a top or upper wall 111 (FIGS. 11, 12, 14 and 15), a front or forward wall 112, and a back or rearward wall 113 (FIGS. 11, 16 and 17). The walls 111, 112 and 113 are supported by a pair of uprights 116 and 117 which in turn are movably mounted on the frame 39 of the machine. With specific reference to FIGS. 11 and 16, the wall 112 and the upright 116 are located on the side of the machine which is adjacent the switch 81, and the wall 113 and the up-

right 117 are located on the side of the machine which is adjacent the conveyor 31. The uprights 116 and 117 include vertically extending angle members 118 and 119, respectively, which as shown in FIG. 11, extend from above the top wall 111 to a location below the horizontal plate 67 of the elevator 40. Each of the members 116 and 117 has secured to the lower end thereof a horizontally extending bracket 120 (FIGS. 9, 10, 12, 15 and 17) which extends underneath the horizontal plate 67 of the elevator 40 and is mounted for sliding movement toward or away from each other on the frame 39 of the machine.

With specific reference to FIGS. 9 and 10, the positions of the two uprights 116 and 117 may be manually adjusted by two adjusting screws 123 rotatably mounted below and adjacent the elevator. The two screws 123 are oppositely threaded and engage nuts 124 which are secured to the two brackets 120. A shaft 126 supports the screw 123 and is rotatably supported on the frame 39 of the machine, and it will be apparent that turning movement of the shaft 126 results in movement of the two uprights 116 and 117 toward or away from each other, depending upon the direction of rotation of the shaft 126.

As previously mentioned, the walls of the magazine are supported by the two uprights 116 and 117, and therefore the distance separating the forward and rearward walls 112 and 113 of the magazine may be adjusted by turning the shaft 126. Such an adjustment is desirable to enable the magazine to accomodate cigarette cartons of different widths, such as the regular width cigarettes and the more recent "thins." In the present construction, an adjustment may be manually made by a hand wheel 131 (FIGS. 1, 4 and 5) fastened to one end of an adjusting shaft 132, the other end of the shaft 132 being connected by a coupling 133 to the shaft 126. The end of the shaft 132 having the hand wheel 131 fastened thereto is rotatably mounted on the supporting frame 134 (FIGS. 1 and 2) for the stamping and gluing machine 29 and the input conveyor 31. A pointer 136 is connected by a worm and gear arrangement 135 to the shaft 132, the pointer 136 being located above the upper surface of the frame 134 as shown in FIG. 4. Indicia 137, consisting in the present instance of numerals 1 through 8, are preferably provided adjacent the end of the pointer 136. Before feeding cigarette cartons into the case packing machine to be repacked in empty cases, the operator turns the hand wheel 131 to set the pointer 136 at one of the numbers 137, this number being associated, by precalculation, with the cigarette carton width being processed. Turning of the hand wheel 131 thus moves the side walls 112 and 113 of the magazine the proper distance apart to receive a tier of six cartons.

In addition to moving the walls 112 and 113, the switch 81 (FIG. 11) is also moved because it is supported by the upright 116. The frame 116 further supports a panel 141 which is positioned between the flange 83 of the plate 82 and the limit switch 81. A slot 142 is formed in the panel 141 at a location adjacent the slot 83b and adjacent an actuator roller 81a of the switch 81, and the roller 81a extends into the slots 83b and 142. As previously mentioned, pressure of the cigarette cartons 66 against the roller 81a causes rotation of the switch 81. Since the switch 81 is mounted on the frame 116, its position will also be adjusted along with the side walls 112 and 113 of the magazine, with the re-

sult that the switch 81 will always be actuated when the sixth cigarette carton is pushed onto the elevator 40 regardless of the carton width.

With reference to FIG. 16, the forward wall 112 of the magazine 41 comprises a fixed panel 146 which is fastened by a bolt 147 to the member 118 and a flexible panel 148 which is fastened by a bolt 148a to the member 118. The panels 146 and 148 extend across the forward side of the magazine from the upright 116 toward the tower 42. The edge of the panel 148 which is adjacent the tower 42 includes an extension 149 which slants inwardly toward the other side wall 113 and telescopes into the open end of a case, indicated in FIG. 16 by the reference numeral 151. The panel 148 and the extension 149 are preferably made of relatively thin sheet metal which is capable of being flexed outwardly when pressure is exerted on it during the time that the cartons 66 are being pushed into the case 151.

With reference to FIG. 16, the other side wall 113 also comprises a fixed panel 156 and a flexible panel 157 which are similar to the panels 146 and 148. The two panels 156 and 157 are secured to the member 119 of the upright 117, and the intermediate panel 157 includes a slanted extension 158 similar to the extension 149.

The pressure bar 101 (FIGS. 11 and 16) is slidably supported by the inner panel 156, the pressure bar 101 including a vertically upwardly extending plate portion 159 which slides between a pair of guides 161 secured to the inner face of the panel 156. With reference to FIG. 16, a spacer 162 is secured to the inner surface of the plate portion 159 to make the inner surface of the portion 159 flush with the surfaces of the two guides 161.

With reference to FIG. 11, the upper wall 111 of the magazine 41 comprises a pair of horizontally extending panels 166 and 167 which are respectively pivotably and slidably connected to two vertically extending shafts 168 and 169 secured to the members 118 and 119. The two panels 166 and 167 support two vertically extending panels 171 and 172, respectively, which extend downwardly from the panels 171 and 172 on the outsides of the panels 148 and 157 of the sidewalls. Brackets 173 pivotably and slidably fasten the panels 171 and 172 to the shafts 168 and 169. The connection of the panels 166 and 167 and brackets 173 with the shafts 168 and 169 permit both vertical sliding movements and pivotal movement of the panels on the shafts. Consequently, pressure against the undersides of the two panels 166 and 167 as cartons of cigarettes are stacked by the elevator into the magazine causes the panels 166, 167, 171 and 172 to move upwardly, thereby enabling the magazine 41 to accomodate cartons of different heights.

As shown in FIG. 11, the inner edges of the two horizontal panels 166 and 167 are spaced apart, and a spanner plate 177 is secured to one of the two panels 166 and 167 and underlies the other panel, spanning the gap between them. Consequently the entire upper side of the magazine is closed by the two panels 166 and 167 and the spanner plate 177. Further, a tension spring 178 (FIGS. 6 and 13) is connected between the two panels 166 and 167 on the upper sides thereof. This spring 178 pivots the panels 166 and 167 toward each other and it also flexes the panels of the side walls toward each other.

With reference to FIGS. 14 to 17, the two panels 171 and 172 of the top wall 41 have extension panels 181 and 182 secured thereto which slant inwardly and telescope into the open end of a case being packed in order to guide the cartons into the case. The panels 181 and 182 are bent to extend horizontally across the top wall of the magazine and a limit switch 183 (FIGS. 13 and 14) is fastened to the upper surface of the horizontal portion of the panel 181. The switch 183 is supported by a bracket 184 on the panel 181, and the bracket 184 further pivotally supports an actuating leaf 186 which is bent upwardly at its ends and pivots on the upper surface of the panel 181 about the point 187. One end of the leaf 186 extends underneath the actuating button 188 of the switch 183, and the other end of the leaf 186 extends to a location where it is within an empty case 151 waiting to be filled. When the magazine is empty or only partly filled, the panels of the top wall are in a relatively low position (shown in solid lines in FIG. 14) and are supported by the side walls of the magazine, and the leaf 186 is out of engagement with the top side of the case 151 in the tower. However, when the tiers of cigarette cartons reaches a certain level, the panels of the top wall are lifted upwardly and the outer end of the leaf 186 engages the top side of the case 157, causing the leaf 186 to pivot on the point 187 and actuate the switch 183. Actuation of this switch 183 occurs only when the magazine is full and the switch energizes the pusher mechanism 43 to push the cartons from the magazine 41 into the case 151 located in the tower 42. As previously mentioned, actuation of the switch 183 further serves to hold the elevator in its upwardly displaced position while the pusher is moving forwardly, whereby the lowermost tier of the cartons in the magazine slides across the upper surface of the elevator as the cartons are being packed into the case 151. As shown in FIG. 14, a stationary plate 189 bridges the space between the elevator and the case 151 and supports the cartons of cigarettes during movement out of the magazine.

With particular reference to FIGS. 3, 6 to 8 and 17, the pusher mechanism 43 for pushing the cartons out of the magazine includes a carriage 201, rails 202 and 203 for supporting the carriage 201, and a pusher plate 204 which engages the cartons of cigarettes. The rails 202 and 203 are V-shaped in cross-section, as shown in FIGS. 7 and 8, and their apexes extend toward each other. The carriage 201 is supported for rolling movement on the rails 202 and 203 by two pairs of rollers 207 and 208. With reference to FIG. 8, the two rollers 208 are rotatably mounted on two angles 209 which form part of the carriage 201. The angles 209 extend in the direction of movement of the carriage and the rollers 207 are mounted at the end of the angles, which is displaced from the magazine 41. The rollers 208 of each pair extend on the upper and lower sides of the rails 202 and 203 as shown in FIG. 8. The other rollers 207 are rotatably mounted on the rails 202 and 203 (FIG. 7) adjacent the magazine 41, and the rollers 207 of each pair extend on the upper and lower sides of the angles 209. Thus, the uppermost of the rollers 207 and 208 support the carriage 201 for rolling movement, and the lowermost of the rollers 207 and 208 prevent tipping of the carriage as it moves.

With particular reference to FIG. 15, secured to the ends of the two angles 209, which are adjacent the magazine 41, is a bracket 211 which supports the

pusher plate 204. The pusher plate 204 is sized relative to the interior of the magazine so that the plate 204 may move through the magazine when the carriage is moved toward the tower. The pusher plate 204 is preferably formed in two sections 212 and 213, the section 212 being fastened to the bracket 211 and the other section 213 being supported by the bracket 211 for vertical sliding movement relative to the other section 212. The position of the movable section 213 may be adjusted by a pneumatic cylinder 214 which is also mounted on the bracket 211. The piston rod 216 of the cylinder 214 is connected to the upper end of the movable section 213, and when the piston rod 216 is extended from the cylinder 214, the panel 213 slides upwardly relative to the section 212. Thus, an adjustment in the vertical dimension of the pusher plate 204 is made possible, such an adjustment being desirable because it enables the pusher plate 204 to accommodate cartons of different heights.

Supported by the movable section 213 and movable with the carriage 201 is a pair of magazine top wall support rollers 217 (FIGS. 15 and 17). As shown in FIG. 15, when the piston rod 216 moves the section 213 of the pusher plate upwardly, the rollers 217 move into engagement with the panels 166 and 167 of the upper wall 111 of the magazine, and when the carriage moves forwardly to push the cartons out of the magazine, the rollers 217 ride along the underside of the top wall. The cartons of cigarettes support the upper wall 111 while the carriage moves forwardly and the rollers 217 support the top wall while the carriage is moving back. The cylinder 214 is slowly vented while the carriage is moving back, permitting the top wall to move slowly down.

Air pressure in the cylinder 214 to move the section 213 upwardly is preferably controlled by a regulator valve at a level which is sufficient to maintain the rollers 217 against the top wall of the magazine but not enough to push the top wall upwardly. Air to the cylinder 214 is controlled by the air solenoid which also controls a pneumatic case centering mechanism of the tower 42. Thus, when the pneumatic mechanism is actuated to center a case as will be described hereinafter air pressure will be applied to the cylinder 214 and when the case centering mechanism is released air in the cylinder 214 is slowly vented to the atmosphere as mentioned above.

Movement of the carriage 201 is effected by a pneumatic cylinder 221 which, as shown in FIG. 7, is fastened to the frame 39 of the machine below the carriage 201. The end of the cylinder piston rod 222 (FIGS. 12 and 16) is secured to the bracket 211 whereby, when air is admitted to the cylinder 221 behind its piston, the piston rod 222 is extended and the entire carriage including the pusher plate 204 is moved forwardly to push cartons of cigarettes out of the magazine 41, as shown in FIG. 17. When pressure behind the piston is released and air is admitted to the cylinder 221 ahead of the piston, the rod 222 is retracted into the cylinder 221 and the carriage 201 is withdrawn to its home position (FIG. 16).

As previously mentioned, the pusher mechanism 43 is actuated to move forwardly by the switch 183, actuation of the switch 183 indicating that the magazine 41 is full as previously explained. The switch 183 actuates a valve 43a (FIG. 3) which controls air to the cylinder 221 to cause the piston rod 222 to be extended. When the carriage 201 has moved forwardly to its fully ex-

tended position, shown in FIG. 17, a cam 224 secured to one of the two angles 209 of the carriage engages a limit switch 226 mounted on the frame of the machine. The switch 226 is also connected to the valve 43a and causes retraction of the carriage 201. The carriage moves back until the piston rod 222 is fully retracted into the cylinder 221, and when the carriage 201 is fully retracted (FIG. 16), another cam 227 on one of the angles 209 engages another limit switch 228 fastened to the frame of the machine adjacent the switch 226. The switch 226 is connected in the control circuit for the elevator such that the elevator cannot move up until the carriage is fully retracted and the switch 226 is actuated. A control valve 231 (FIG. 17) is mounted on the frame of the machine adjacent the carriage and controls pneumatic devices of the tower 42 as will be explained.

As previously mentioned, the carriage of the pusher mechanism 43 pushes a stack of cartons out of the magazine 41 and into an empty case 151 which has previously been positioned and centered in the tower 42. The tower 42 is generally rectangular in shape and has an open upper side. As previously mentioned, empty cases positioned by the operator on the overhead conveyor 36 (FIGS. 1 and 2) are carried upwardly by moving belt 241 (FIG. 3) which is continuously driven by a belt-drive 242 connected to the main drive of the packing machine. The belt 241 moves the cases along a pair of laterally spaced tracks 243 (FIGS. 1 and 3), the tracks 243 curving downwardly and toward the right as seen in FIG. 3 so that a case, after it leaves the belt 241, slides by force of gravity into the upper end of the tower 42. Since the open side of the case 151 is facing downwardly while it is moving on the conveyor 36, the open side of a case will be facing toward the magazine 41 after it has fallen into the tower 42. Movement of a case 151 downwardly into the tower causes it to actuate a switch 246 (FIG. 13) located at the bottom end of the tower. The case 151 moving into the tower comes to rest on a plurality of rollers 247 which form the bottom wall of the tower. One of the rollers 248 has one end thereof mounted for slight vertical movement, and the actuating finger 249 of the switch 246 is located underneath this roller 248. When a case 151 rests on the rollers 247 and 248, the weight of the empty case causes the movable roller 248 to shift downwardly slightly and actuate the switch 246.

Actuation of the switch 246, indicating that a case 151 has dropped into the tower 42, energizes a case positioning mechanism 251 and a case centering mechanism 252 (FIGS. 9 and 14). The switch 246 also controls air pressure to the air cylinder 214 of the pusher plate so that air pressure is applied as soon as a case drops into the tower. The case positioning mechanism 251 is located on the side of the tower 42 which is opposite the magazine 41, and is designed to push a case 151 tightly over the slanted extensions of the side walls and the top wall of the magazine in telescoping relation as shown in dashed lines in FIG. 14. The positioning mechanism 251 comprises two vertically spaced, horizontally extending rods 256 and 257 (FIGS. 4 and 14) which are pivotally mounted on the frame of the machine. Two arms 258 are secured to each rod 257 and 256 adjacent the ends thereof, and a roller 259 is rotatably mounted between the outer ends of each pair of the arms 258. The two rods 256 and 257 are connected to be pivoted by a lever 261 secured to approximately

the center of each rod. A link 262 pivotally connects the outer ends of the two levers 261 and is also pivotally connected to the end of the piston rod 263 of a pneumatic cylinder 264, which is mounted on the frame of the machine. Thus, the two pairs of arms 258 may be moved between a retracted position shown in full lines in FIG. 14 and an extended position shown in dashed lines in FIG. 14, by movement of the piston rod of the cylinder 264. When the piston rod 263 is moved upwardly, the levers 261 and the arms 258 swing counterclockwise as seen in FIG. 14 to the retracted position, and when the piston rod 263 is pulled or withdrawn into the cylinder 264, the arms 258 are pivoted in a clockwise direction to move the rollers 259 in the direction of the magazine.

With reference to FIGS. 9 and 13, the case centering mechanism comprises a pair of angles 271 and 272 which are positioned on opposite sides of the tower and extend in the direction of movement of the cartons as they are pushed out of the magazine. The two angles 271 and 272 are pivotally supported on the frame by pins 273 adjacent the case positioning mechanism. The other ends of the two angles 271 and 272, which are the ends adjacent the magazine, are connected together by a pneumatic device including a cylinder 274 and a rod 275, the cylinder 274 being attached to the angle 271 and the piston rod 275 of the cylinder being attached to the other angle 272. Thus, when the piston rod of the cylinder 274 is retracted, the angles 271 and 272 are pivoted toward each other about the pins 273. Attached to the ends of the angles 271 and 272, which are adjacent the magazine are two uprights 276 (FIGS. 6 and 16) which extend vertically along the outer sides of the extensions 181 and 182 of the magazine. When the rod 275 is retracted into the cylinder 274 to pull the two angles 271 and 272 toward each other, the opposite side walls of the tower and the uprights 276 move toward each other and center the carton relative to the magazine. Stops 276a (FIGS. 16 and 17) fastened to the uprights 276 extend inwardly and are adapted to abut the side walls of the magazine in order to prevent the case centering mechanism from pinching a case.

Air to the cylinders 264 and 274 is controlled by a solenoid actuated valve 270 (FIG. 3) which in turn is controlled by the switch 246. Thus, the case positioner 251 and the case centering mechanism 252 are simultaneously energized, but flow control devices connected to the cylinders cause the case centering mechanism to act more rapidly than the case positioning mechanism so that, first, the case is centered and secondly, the case positioning mechanism 251 pushes the case toward the magazine and over the slanted extensions 181, 182 and the upper extension 166. The case 151 is thereby telescoped onto the end of the magazine enabling the cartons to be easily pushed into the case without snagging.

Energization of the pusher mechanism 43 causes the cartons to be pushed from the magazine 41 into the case 151, as previously explained, and pressure exerted by the pusher mechanism against the cartons after being pushed into the case causes the two rollers 259 to be pushed back against the force exerted by the pneumatic cylinder 264 of the case positioning mechanism 251. After a predetermined amount of such movement, the cartons are tightly packed in the case and the switch 226 is actuated. The switch 226 actuates the valve 270 to reverse the air pressure in the cylinders 264 and 274 to retract the rollers 259 and the uprights

276, and release the case. As previously mentioned, the switch 226 also causes retraction of the carriage 201. When the carriage moves back and the cartons are out of the magazine, the switch 183 is released permitting the elevator to move downwardly and the bar 101 to rise.

As soon as the case centering and case positioning mechanisms are released, a door between the tower 42 and the output conveyor 33 is opened, and an ejector mechanism is operated to push the filled case out of the tower and onto the conveyor 33. The door comprises a pair of flaps 286 and 287 (FIGS. 6 and 16) which are pivotally mounted on opposite sides of the tower adjacent the conveyor 33. Each of the panels 286 and 287 is secured to a vertically extending post 288 (FIG. 16) which is pivotally mounted on the frame of the machine. In order to pivot the posts 288 and the two door flaps 286 and 287, a pneumatic cylinder 290 (FIG. 9) is pivotally connected between the two posts 288. The cylinder 290 is connected to one of the two posts by a right angle shaped link 291, and the piston of the cylinder 290 is connected to the other post by another right angle shaped link 292. The connections between the links 291 and 292 and the posts 288 are rigid, whereas the connection of the pneumatic cylinder 290 and its piston rod with the links 291 and 292 is pivotal. It will be apparent, therefore, that when the piston rod is retracted into the cylinder 290, the door flaps 286 and 287 will be swung open as shown in FIG. 17, and when the piston rod is forced out of the cylinder 290, the door flaps will be swung to their closed positions shown in FIG. 16.

With specific reference to FIGS. 13 and 17, the case ejector mechanism comprises a vertically extending kicker plate 296 which is pivotally mounted on the frame of the machine. A lever 298 is secured to the upper end of the kicker plate 296 and to a shaft 297 which is pivotally mounted on the frame of the machine, and the lever 298 is pivotally connected to the piston rod 299 of a pneumatic cylinder 301. The lower end of the cylinder 301 is pivotally fastened to the frame of the machine. When the cylinder 301 is actuated to retract the piston rod 299, the lever 298 and the kicker plate 296 are pivoted in the counterclockwise direction, as shown by the dashed lines in FIG. 13, thereby ejecting a case out of the opened door of the tower and onto the conveyor 33. As soon as a filled case has been ejected, the kicker plate 296 pivots slowly in the clockwise direction as seen in FIG. 13 as it returns to its normal position shown in full lines in FIG. 13. Assuming that another empty case had been resting in the tower on top of the case being ejected, this empty case drops onto the top side of the kicker plate as soon as the filled case has been ejected, and as the kicker plate 296 pivots downwardly in the clockwise direction, the empty case slides downwardly in the tower and drops onto the rollers 247 and 248 and actuates the switch 249, thus actuating the case positioning mechanism 251 and case centering mechanism 252, as previously explained.

Air to the pneumatic cylinders 290 and 301 is controlled by the valve 231 (FIGS. 3, 6 and 17) previously referred to. The valve 231 is mounted on the frame of the machine above the carriage 201 and has two oppositely extending actuator buttons 302 and 303. Bolts 304 and 305 fastened to the carriage 201 on opposite sides of the valve 231 are located to actuate the buttons

302 and 303. When the carriage has moved forwardly to pack cartons in a case, the bolt 304 engages the button 302 and causes opening of the flaps 286 and 287 and actuation of the ejector mechanism. When the carriage has returned to its rearward position, the bolt 305 engages the button 303 and causes the flaps 286 and 287 to close and the kicker plate 296 to swing down. The cylinder 301 is preferably constructed to release air slowly so that the plate 296 and a case thereon move down slowly.

As previously mentioned, the cartons are fed into the magazine 41 with the open flaps 66a on the upper sides thereof, and at least one of the opened flaps of each carton has a bead of glue formed thereon. While the flaps of the cartons in the lowermost tiers of a stack in the case may be well sealed due to the pressure exerted by the weight of the cartons above them, the cartons in the uppermost tier may not have their flaps pressed firmly together, and therefore a firm seal may not be effected on the cartons in this uppermost tier. It is desirable therefore that the case, after leaving the tower 42 and moving along the output conveyor 33 be turned end-for-end in order to place the opened flaps of the cartons on the undersides thereof. This function is accomplished by the inverter mechanism 34 (FIGS. 1 and 18 through 23).

With specific reference to FIG. 18 and 19, the case inverting mechanism comprises a box-like frame 311 which extends across the underside, upwardly from the sides of the conveyor 33, and across the top of the conveyor. The frame includes two generally horizontally extending cross members 312, one of which is spaced above each side of the conveyor 33 and extends generally parallel thereto. A shaft 313 is rotatably mounted between the two cross members 312, and two spaced-apart I-shaped frames 314 are secured to the shaft 313, the shaft 313 extending approximately through the center of the web of the frame 314. The two frames 314 are separated by a distance which is less than the width of a case. The distance from the shaft 313 to the cross members at each end of the web of each frame is such that, when the web of each frame is generally vertical as shown in solid lines in FIG. 18, the lower cross member thereof is slightly below the upper surface of the conveyor 33 where the cases enter the inverter. As shown in FIG. 19, the conveyor 33 is in the present instance a roller conveyor and openings are provided in the conveyor 33 for the cross members of the frames.

The shaft 313 and the two frames 314 are turned by an electric motor 321 connected to the shaft 313 by a drive including a belt 320 and pulleys 322 and 323. A shaft 324 supports the pulley 323 and is secured to a worm 326 which in turn drives a spur gear 327. The gear 327 is connected through a cross shaft 328 to a pulley 329, the latter pulley 329 being connected by a belt 331 to a relatively large pulley 332 secured to an end of the shaft 313. It will be apparent that rotation of the motor 321 turns the worm 326 and gear 327, the pulley 332 and the shaft 313.

Energization of the motor 321 is controlled by a normally open electric switch 336 fastened to the conveyor 33 within the confines of the frame 311. As shown in FIG. 22, a flexible leaf 337 is fastened to the conveyor 33 above an actuator button 336a of the switch 336, and movement of a case onto the portion of the conveyor 33 which is within the frame 311 causes the leaf 337, which normally extends above the

upper surface of the conveyor 33, to be flexed downwardly and press the button 336a of the switch 336.

FIG. 23 shows the control circuit for the motor 321. The motor 321 is connected in series with the switch 336 and across the terminals 338 of a power supply. When the normally open switch 336 is closed by a case pressing against the leaf 337, the circuit path through the motor 321 is closed and the motor 321 starts to turn the frame 314 in the clockwise direction as seen in FIG. 18. As shown by the dashed line position of the frame 314 and the case in FIG. 18, the lower cross members of the two frames extend under the case and lift the case upwardly off the switch 336, permitting the switch 336 to open. However, the motor 321 continues to be energized for one-half a complete revolution of the frames 314 by a cam device 339 which is also turned by the shaft 313. The cam 340 of the device 339 is generally circular but has two reduced diameter portions 341 and 342 in the outer periphery thereof, and a normally open switch 343 includes a rider or actuator 344 which rides on the cam 340. The rider is normally in one of the reduced portions 341 and 342 but, as soon as the motor 321 is energized, the shaft 313 and the cam 339 rotate and the rider 344 moves outwardly to the outer or raised surface of the cam 339, thus closing the switch 343. The switch 343 is connected in parallel with the other normally open switch 336. Thus, as soon as the switch 336 is closed and initiates operation of the motor 321, the switch 343 is also closed and holds the motor 321 energized even though the switch 336 opens until the shaft 313 has turned one-half revolution and the rider 343 drops into the other reduced diameter portion of the cam 340. Movement of the two frames 314 with a case thereon through a 180° arc therefore results in the case being picked up by the lower cross arms of the two frames 314, swung upwardly as shown in dashed lines in FIG. 18, and deposited on the conveyor 33 once again on the opposite side of the inverter 34. After a little more than 90° turning movement of the frames 314, the case slides along the webs of the frames and then rests against the cross members at the opposite ends of the frames. Since the two I-shaped frames 314 are symmetrical, the two I-shaped frames will again be in position to receive the next subsequent case as it rolls down the conveyor 33 to the inverter 34.

In summary, an operator of the machine first adjusts the width of the magazine and the elevator using the handwheel 131, in accordance with the width of a series of cigarette cartons being processed, empties the cartons from a cut case and feeds the cartons into the stamping and gluing machine 29. At the same time, the empty case is placed on the conveyor 36 which carries it to the tower 42 where it drops onto the loading platform ahead of the time that all of the cartons associated with the case are stacked in the magazine. The packing machine receives cartons of cigarettes from the stamping and gluing machine 29 with the open flaps of the cartons extending upwardly and with a bead of glue thereon. The cartons are successively fed sideways onto the elevator 40, and when six cartons are on the elevator, the switch 81 is actuated to move the elevator up and the cartons into the magazine. The manner in which the cartons are fed onto the elevator is advantageous because only one switch 81 is required rather than a plurality of switches as in prior art constructions. The hold-down bar 101 is highly advantageous because it firmly holds cartons of cigarettes on the input con-

veyor while the elevator is moving upwardly, thus preventing cocking of the cartons. The hold-down bar is further advantageous in that, when actuated, it presses down until stopped by a carton of cigarettes, whereby the bar is able to accomodate cartons of different heights. The magazine 41 into which the cartons are stacked by the elevator is adjustable both in width and height, thereby enabling the machine to receive different sizes of cartons. The mechanism for positioning an empty case tightly against the magazine is advantageous in that it includes a simplified mechanism for pushing a case against the magazine. The case centering mechanism serves the important function of centering cases, regardless of width, on the magazine. After the cases are repacked with the cartons associated therewith and ejected onto the output conveyor, the inverter 34 inverts an entire case at a time, thereby eliminating the need for a relatively complicated mechanism for turning each carton over.

I claim:

1. In a case packing machine for packing series of cartons into empty cases, the width of the cartons of some of said series being different from the width of the cartons of other of said series and the width of each case being related to the width of the series of cartons associated therewith, the improvement in said packing machine comprising a magazine, an elevator for stacking tiers of cartons in said magazine, and means for pushing a stack of tiers from said magazine into an empty case, said elevator including first support means for supporting said cartons, said cartons being fed in succession onto said first support means from an entrance side thereof, second support means slidably relative to said first support means and forming an extension from the side of said first support means which is opposite said entrance side, said second support means including an upstanding portion which extends upwardly above the level of said first support means and is adapted to extend in the path of cartons moving onto said first support means, a plurality of cartons moving on said first and second support means forming a tier and engaging said portion and sliding said second support means away from said entrance side, whereby said first and second support means are capable of accommodating tiers of cartons of different widths, said elevator further including drive means for moving said first and second support means with a tier thereon into said magazine.

2. Apparatus as in claim 1, and further including a switch positioned on the side of said elevator which is opposite said entrance side, said switch being positioned in the path of said upstanding portion and being adapted to be actuated thereby when a tier of cartons is on said first and second support means, and said switch being connected to energize said drive means when actuated.

3. Apparatus as in claim 1, and further including means for adjusting the position of said switch toward or away from said first support means.

4. Apparatus as in claim 3, wherein said adjusting means is further connected to said magazine to adjust the width of said magazine.

5. In a case packing machine for packing series of cartons into empty cases, the width of the cartons of some of said series being different from the width of the cartons of other of said series, the width of each case being related to the width of the series of cartons asso-

ciated therewith, and each case having an empty side, the improvement in said packing machine comprising a magazine, an elevator for stacking tiers of cartons in said magazine, a tower for positioning an empty case adjacent said magazine, and means for pushing a stack of tiers from said magazine into the empty case, said tower comprising means for supporting a case with said open side facing said magazine, means in said tower for centering said case relative to said magazine, said centering means comprising a pair of members, said members extending adjacent opposite sides of said tower and adapted to extend adjacent the walls of a case to be centered, and power means connected between said pair of members for moving said pair of members equal distances toward and away from each other when actuated, whereby a case is centered by movement of said members toward each other, and means positioning said case tightly against said magazine.

6. Apparatus as in claim 5, wherein said case positioning means and said case centering means each includes drive means, and a common actuator is connected to actuate said drive means.

7. Apparatus as in claim 6, wherein said drive means for said centering means acts more rapidly than said drive means for said case positioning means.

8. In a case packing machine for packing series of cartons into empty cases, the width of the cartons of some of said series being different from the width of the cartons of other of said series, and the width of each case being related to the width of the series of cartons associated therewith, the improvement in said packing machine comprising a magazine, an elevator for stacking tiers of cartons in said magazine, a tower for positioning an empty case adjacent said magazine with an open side of the case facing said magazine, and means for pushing a stack of tiers from said magazine into the empty case, said elevator including first and second means for supporting said cartons, said second means being slidable relative to said first means and forming an extension from one side thereof, said magazine including two spaced-apart side walls, means supporting said side walls for movement toward and away from each other, and said tower comprising means for positioning an empty case relative to said magazine.

9. A case packing machine for packing series of cartons into empty cases, comprising a magazine, an elevator for stacking tiers of cartons in said magazine, said magazine being vertically displaced from said elevator and said elevator including a platform which moves vertically to stack tiers in said magazine, continuously moving conveyor means leading to an entrance side of

said elevator for feeding cartons successively onto said elevator, said platform comprising a first support adjacent said conveyor and a second support which is slidably fastened to said first support and forms an extension thereof, and hold down means including a movable bar mounted between said elevator and said conveyor for clamping the carton most closely adjacent said elevator during the time that said elevator is moving a tier of cartons into said magazine, said elevator including power means for effecting said vertical movement of said platform, and said hold down means includes power means for moving said bar to clamp said carton, and further including a switch fastened to and movable with said second support of said platform and actuated by said cartons moving thereon for simultaneously actuating both of said power means.

10. Apparatus as in claim 9, wherein said power means for said hold down means presses said bar downwardly until stopped by a carton of cigarettes, whereby said hold down means is capable of accommodating cartons of different heights.

11. Apparatus for handling cartons of cigarettes received from a stamping and gluing machine, the machine being adapted to receive cartons having two opened flaps on one side thereof extending upwardly and having a bead of glue on at least one of the opened flaps, said machine comprising a generally flat horizontally extending elevator adapted to have the cartons pushed successively thereon, a magazine positioned above said elevator, said elevator moving a plurality of cartons upwardly into said magazine whenever a predetermined number of cartons has been accumulated on said elevator, said magazine receiving said cartons with said opened flaps thereof extending upwardly, a tower located adjacent said magazine for positioning and centering an empty case to receive cartons from said magazine, pusher means for pushing a stack of cartons from said magazine into an empty case in said tower, means for ejecting a filled case from said tower onto an output conveyor, and inverter means on said output conveyor for lifting each case off said conveyor, turning each case end-for-end to place said glued flaps on the undersides of said cartons, and replacing each of said cases on said conveyor.

12. Apparatus as in claim 11, wherein said inverter means comprises a frame, drive means for turning said frame one-half revolution upon actuation thereof, and switch means for said drive means, said switch means being located to be actuated by each case moving into said inverter means.
